FINISHING TOOL

Anthony Cocozella, Lynn, Mass., assignor to
United Shoe Machinery Corporation, Borough
of Flemington, N. J., a corporation of New
Jersey

Application July 25, 1939, Serial No. 286,417

13 Claims. (Cl. 51—190)

This invention relates to finishing tools and is herein illustrated, by way of example but not of limitation, as embodied in a buffing roll for smoothing, polishing, or abrading the bottoms 5 of shoes.

After a shoe has been assembled, it is customary, as a part of the finishing operations, to buff the sole and frequently the heel breast of a shoe in order to remove any slight imperfections 10 or discolorations and to prepare the shoe bottom to receive the finishing liquids. In those shoes in which both the heel breast and the sole must be buffed, operators experience great difficulty in reaching the portion of the shoe bottom at and 15 adjacent to the junction of the sole and heel breast, especially if this junction forms a sharp corner. To reach into these close corners it has heretofore been necessary to use a flat disk having a radial buffing surface or to perform the 20 operation by hand. Certain disadvantages are attendant upon the use of a flat disk, however, chief among these being that the direction of the buffing is crosswise of the heel breast rather than lengthwise so that if there is any lateral curvature 25 to the heel breast the disk operates unsatisfactorily. Heretofore, the use of a spindle with a buffing sleeve has also been found unsatisfactory since it is not possible with such a tool to reach into the corners of the work piece being 30 operated upon.

With these considerations in view, it is an object of the present invention to provide a finishing tool with which it will be possible to reach into difficult corners such as those found in shoe bottoms at the junction of the sole and a Continental or an Argentine heel. Accordingly, the invention provides a buffing roll having a plurality of peripheral surfaces which intersect to form a number of salient portions projecting 35 radially outward from the body of the roll and extending longitudinally thereof. Through the provision of these salient portions an operator may, when the roll is rotated, reach into and buff mechanically many places which he would be unable 40 to reach with an ordinary cylindrical roll of comparable diameter.

The invention will be better understood when considered with relation to the accompanying drawing, in which

50 Fig. 1 is a side view of the buffing tool, a portion being broken away to show its structure;

Fig. 2 is an end view of the tool illustrated in Fig. 1;

Fig. 3 is a view similar to Fig. 1 showing a modified form of the tool;

Fig. 4 is an end view of the tool illustrated in Fig. 3;

Fig. 5 is an end view of another modification of the invention; and

Fig. 6 illustrates the tool operating on a shoe. 5

As illustrated in Figs. 1 and 2 the invention comprises a soft rubber roll 10 which is hollow and has a triangular cross section. The corners 12 of the roll are rounded slightly and constitute salient portions which project radially 10 outward from the body of the roll and extend longitudinally of the roll, thus forming the working sections of the roll. When the roll is to be used for abrading rather than polishing or buffing, an abrasive sleeve 14 may be slipped over 15 it, fitting tightly about its periphery. The roll is supported on a rotatable shaft 16 which extends lengthwise of the roll to provide adequate radial support. Preferably, as illustrated in Fig. 1, the shaft is reduced in diameter at 18 so that 20 its end portion 20 does not come in contact with the roll. Thus when a work piece is pressed against the roll, the end portion will yield to an extent limited by the reduced end portion 20 of the shaft. 25

Use of this tool is particularly advantageous in that type of shoe wherein the heel breast and the sole form a sharp angle. To use the roll on such a work piece, the operator presses the work firmly against the roll, forcing the inner surface 30 of the roll into contact with the end portion 20 of the shaft. It has been found by experiment that when the roll is rotating against such a work piece at a speed substantially slower than that at which ordinary buffing tools are operated, the 35 corners 12 of the roll first strike against the heel breast B and the sole O. On further rotation of the roll, the corners press the abrasive sleeve against the surfaces of the heel breast and the sole and rub the abrasive across it. As the side 40 of the roll approaches parallelism with the heel breast or the sole, depending on the direction of rotation, the distortion of the roll caused by the pressure of the work against it decreases and the resiliency of the rubber tends to force the corner 45 12 of the roll into the corner formed in the work piece, thus enabling the operator to smooth those portions of the heel breast and the outsole which are close to the corner and which he would be 50 unable to reach with an ordinary cylindrical roll. 55

As pointed out, the roll is rotated at speeds substantially slower than those at which ordinary buffing tools are operated. The most satisfactory speed will, of course, be dependent on the angular disposition of the surfaces operated 55

upon, the nature of the material, and other factors, but for most purposes a speed of between 100 and 150 R. P. M. will be found suitable.

Alternatively, as illustrated in Figs. 3 and 4
5 the roll may be formed as a hollow cylinder 22,
one section 24 of which is square in cross section.
In such case, the cylindrical portion of the tool
serves as a convenient means for buffing other
parts of the shoe bottom, either as a complete
10 operation or for touching up spots that were not
properly buffed before. If desired the roll may
be mounted on a short shaft 26 which extends
into the roll only as far as the square section 24.

The abrasive sleeve 14 which fits over the roll
15 may in such case be cemented to the cylindrical
portion thereof. Figs. 3 and 4 illustrate the
manner in which the sleeve fits loosely over the
square section 24 of the roll and comes in contact
20 with it only at its corners 28. When the
loose sleeve is first pressed in engagement with a
work piece, it quickly assumes the shape of the
surface of the supporting roll. Any wrinkles
formed in the course of this conformation do not,
however, interfere with the efficiency of the
25 operation of the tool.

As pointed out the roll is made of a relatively
soft rubber. It may, therefore, be found desirable,
particularly if a short shaft is used, to provide
extra stiffness for the corners of the roll.
30 For this purpose, a number of pins 30 may be
provided. These pins are embedded in the body
of the roll at its corners and provide some additional
support against distortion when a work
35 piece is pressed against the roll. They should
not, however, be so stiff as to eliminate completely
the resiliency of the roll.

In some shoes having very high heels the angle
between the sole and the heel breast may be so
sharp that it is desirable to use a tool modified,
40 as in Fig. 5, so as to have only two longitudinally
extending salient portions. This roll may, of
course, be mounted on a short shaft 26 as illustrated
in Fig. 3 or on a shaft 16 having an end portion
45 reduced in diameter as illustrated in Fig.
1. Such a modification does not affect the principles
of operation of the tool, since the prominences
act in substantially the same manner as they do in the triangular or square roll.

It will be obvious to those skilled in the art
50 that considerable variation may be made in the
tool to suit various types of work. For example, if it is to be used on a heel breast having
a slight lateral curvature, the roll may be curved
longitudinally to correspond therewith as illustrated
55 in Fig. 3. Similarly if the roll is to be used
on work having parts which form obtuse angles,
the roll may be made with more than three or four sides, so that it is polygonal in cross section, "polygonal" being used here and in the
60 claims to include both rectilinear and curvilinear polygons. Such modifications are, of course, clearly within the scope and fundamental spirit
of the invention.

Having thus described the invention, what I
65 claim as new and desire to secure by Letters Patent
of the United States is:

1. A rotary finishing tool comprising a resilient

roll having not more than four salient portions
projecting radially outward from the body of said
roll and extending longitudinally of said roll.

2. A rotary finishing tool comprising a resilient
5 roll one section of which has not more than four
peripheral surface portions which intersect to
form salient portions projecting radially outward
from the body of said roll and extending longitudinally
of said roll.

3. A rotary finishing tool comprising a resilient
10 roll having a flat peripheral working surface.

4. A rotary finishing tool comprising a resilient
roll having a flat working surface substantially
parallel to its axis of rotation.

5. A rotary finishing tool comprising a resilient
15 roll one portion of which has a polygonal radial
cross section.

6. A rotary finishing tool comprising a resilient
roll one portion of which is square in cross
20 section.

7. A rotary finishing tool comprising a resilient
roll one portion of which is triangular in cross
section.

8. A rotary finishing tool comprising a resilient
roll having a peripheral working surface one
portion of which is flat and substantially parallel
25 to its axis of rotation and another portion of
which is cylindrical.

9. A rotary finishing tool comprising a resilient
30 roll having not more than four longitudinally
extending salient portions projecting radially
outward from the body of said roll, and a
plurality of stiffening pins embedded in said roll.

10. A rotary finishing tool comprising a rubber
35 roll one section of which has not more than four
peripheral surfaces intersecting each other to
form longitudinally extending prominences, and
a plurality of stiffening members embedded in
said roll adjacent said prominences.

11. A buffering device comprising a rotatable
40 shaft one portion of which is reduced in diameter,
and a buffering roll having not more than four
longitudinally extending salient portions projecting
radially outward from the body of said roll, said
roll being mounted on said shaft 45 and overextending said reduced portion in spaced
relation thereto.

12. A buffering device comprising a rubber roll
45 having a peripheral working surface and having
one portion which is polygonal in cross section,
a rotatable shaft on which said roll is mounted,
a plurality of pins embedded in the corners of the
50 polygonal portion of said roll, and a sleeve of
abrading material fitting over said roll.

13. A buffering device comprising a rotatable
55 shaft one end of which is reduced in diameter,
a rubber roll mounted on said shaft overextending
said reduced end in spaced relation thereto
and having one portion which has a polygonal
radial cross section and another portion which
60 has a cylindrical radial cross section, a plurality
of stiffening pins embedded in said roll at the
junctions of the straight sides of said polygonal
portion, and a sleeve of abrading material fitting
closely about said cylindrical portion and extending
65 loosely over said polygonal portion.

ANTHONY COCOZELLA.
